UNITED STATES PATENT OFFICE.

OTIS J. ROGERS, OF WASHINGTON, DISTRICT OF COLUMBIA.

FACIAL LIFTING AND SUPPORTING DEVICE.

Application filed July 2, 1926. Serial No. 120,072.

This invention relates to lifting and supporting devices for the facial muscles and the object of the invention is to provide such a device as will lift the muscles of the face and at the same time hold them in the lifted position.

One object of the invention is to provide a combined muscle lifter and muscle supporter, the muscle lifter of which may be employed independently of the muscle supporter.

Another object of the invention is to provide a device of the type indicated which is simple in construction, which may be economically manufactured and which is efficient in function.

Still another object of the invention is the provision of a device of the type indicated which does not require the services of a skilled operator to apply the same in order that it may function efficiently.

I accomplish the above and other objects of the invention by means of the device shown in the accompanying drawings in which

Figure 1 is a perspective of the muscle lifting element in position on a woman's head;

Figure 2 is a view of a pair of adhesive elements which serve to maintain the device in proper position on the head;

Figure 3 is a section on the line 3-3 of Figure 2;

Figure 4 is a view showing the adhesive elements and the elastic lifting element detached;

Figure 5 is a view of the entire device in position on a woman's head; and

Figure 6 is a plan view of the supporter element.

On the drawings, in which like reference characters indicate like parts on all the views thereof, 1 indicates one of the adhesive tabs which is formed of suitable gummed material such as adhesive tape. The adhesive tab is slightly rounded in contour and has a straight upper edge substantially the width of the tab to which is attached a metal loop 2. The loop is secured to the tab by slipping the straight end 3 of the tab through the loop and pressing the adhesive end surfaces against each other until they adhere. The overlapping adhering surfaces should be of material extent so that there will be no

tendency for them to become separated when there is a strain placed upon the loop.

4 indicates the elastic head band, this band being adjustable in length by means of a looped connection with a sliding buckle 5. The elastic band is also provided with a pair of open metal hooks 6, one of the hooks being attached to one end of the elastic band and the other hook being slidably mounted in the adjustable looped end of the band.

6^a indicates the muscle supporter strip formed of knitted fabric, which is inelastic in the direction of its length and slightly elastic in the direction of its width. Each end of the strip has a V-shaped cut-out so as to form two projecting tabs 7 to which are secured loops 8 similar to the loops 2 on the adhesive tabs. The fabric is then bound around the edges with inelastic material such as silk tape or ribbon 9, thus preventing the strip from losing its shape during use.

In order to protect the adhesive surfaces of the tabs 1 when not in use, a piece of material 10 impervious to the adhesive on the tab is disposed between two tabs. Referring to Figure 3 it will be seen that the adhesive 80 united portions of the tabs, carrying the loops 2, will not present an adhesive surface to the impervious material but will be free therefrom so that the loop and the loop carrying portion may be readily grasped in 85 order to remove the tab from the impervious material. Any suitable impervious material may be employed, but it has been found that crinoline is well adapted for the purpose, since the adhesive will not pass 90 through it and it will not leave any lint or other undesirable residue on the adhesive surface.

In order to use the improved muscle lifter and supporter, the tabs are removed from the impervious material and pressed against the face just in front of the ears. The exact spot for applying the tab can be ascertained by lifting the skin with the fingers in this region of the face. The overlapped edge of the tab 95 prevents the hair from sticking to the tab and causing annoyance to the wearer.

After the tabs have become firmly adhered to the skin, the strap hooks are engaged with the tab loop and the strap placed over the head and the proper adjustment made. It is to be noted that the tabs are made of such width that, when properly placed and an

trical energy to cause the disk 25 to rotate continuously. The blank 45 is then placed upon the table 11 in the manner illustrated in Fig. 1 wherein the edge 50 is aligned with the left hand edge (Fig. 1) of the bar 15 and a portion of the edge 49 is inserted under the undercut shoulder 18, the periphery of the disk being engaged by the stops 24. The operator then advances the blank 45 and the table 11 toward the bolt 20 and the disk 25 skives the edge 50, the disk 25 having been adjusted to give the correct width and taper to the skive. It will be noted that the disk 25 cannot engage and injure the edge 49. After the edge 50 has been skived the table 11 is returned to the position wherein it is shown in Fig. 1 and the blank 45 is turned over and so positioned that its edge 49 is aligned with the left hand edge (Fig. 1) of the bar 15 and its edge 50 is protected due to the raising of the edge 49 by the undercut shoulder 18. The operator again advances the blank 45 and the table 11 toward the bolt 20 to skive the edge 49 and then returns the table to the position wherein it is shown in Fig. 1 so that the blank may be removed from the table. In each of the skiving operations, the resilient finger 42 prevents the blank from buckling as it passes beneath the disk 25.

The use of the disk 25 of abrasive material is advantageous in that neat and accurate

skives are formed upon the paper blanks, a result which cannot be obtained by the use of knives or rotary cutters. In practice it 35 has been found that even a sharp knife will tear the blank in such manner that a ragged skive is produced. It has also been found that the paper from which the blanks are formed contains an appreciable amount of 40 gritty substances which rapidly dull tools having cutting edges. These substances do not affect the operation of the disk 25 to any appreciable extent as the disk may be dressed from time to time in a manner well known to 45 those skilled in the art.

What is claimed is:

1. In an apparatus for skiving the edges of a slit in flexible material to form a joint, a table for supporting the material, a bar for aligning one edge of the slit and forming a recess with the table to receive the other edge of the slit, and supporting the material adjacent said edge, and means for skiving the aligned edge. 50

2. A method of skiving an edge of a slit, which consists of separating the edges of the slit, supporting one edge of the slit above the other edge, and skiving a supported edge. 55

In witness whereof, we hereunto subscribe our names this 17th day of November A. D., 1924.

WILLIAM HARRY RAY.
MARION LLEWLLYN STRAWN.
